(57) **CLAIM**

The ornamental design of an insulated beverage container, as shown and described.

DESCRIPTION

FIG. 1 is a perspective view of an insulated beverage container embodying the design of the present invention; FIG. 2 is a back side view of the insulated beverage container illustrated in FIG. 1;

FIG. 3 is a front side view of the insulated beverage container illustrated in FIG. 1;

FIG. 4 is a right side view of the insulated beverage container illustrated in FIG. 1;

FIG. 5 is a left side view of the insulated beverage container illustrated in FIG. 1;

FIG. 6 is a top view of the insulated beverage container illustrated in FIG. 1; and,

FIG. 7 is a bottom view of the insulated beverage container illustrated in FIG. 1.

The broken line showing of the insulated beverage container is for the purpose of illustrating portions of the insulated beverage container and forms no part of the claimed design.

1 Claim, 6 Drawing Sheets
